Patented Oct. 2, 1928.

UNITED STATES PATENT OFFICE.

GEORGE HENRY WHEARY AND MATHIAS KURTEM, OF RACINE, WISCONSIN, ASSIGNEES
TO WHEARY TRUNK CO., OF RACINE, WISCONSIN, A CORPORATION OF WISCONSIN.

DRAWER-LOCKING DEVICE.

Application filed August 6, 1924. Serial No. 730,523.

This invention relates to certain new and useful improvements in drawer locking devices and refers more particularly to a device of the character described especially 5 designed for releasably securing the drawers of a wardrobe trunk against unauthorized opening.

It is one of the objects of this invention to provide a combined drawer guide or mount 10 and drawer locking device wherein rigid and substantial means are provided for readily releasably securing the drawers in the drawer section of a wardrobe trunk against unauthorized opening.

15 This invention contemplates as another of its objects the provision of an improved drawer guide or mount having means adapted to be passed through the parts thereof when the drawers are in closed position to releasably lock the drawers against tampering or unauthorized opening.

It is a further object of our invention to provide a non-removable type of locking device for wardrobe trunk drawers wherein a 20 locking bar is provided having a locking tongue for each drawer adapted to be passed through the guide members carried thereby and the section when the drawer is fully closed to firmly and rigidly lock the same against unauthorized opening and thus eliminate 25 the necessity of cutting away a portion of the drawers to provide keeper recesses or the securing thereto of special keeper devices.

30 A still further object of our invention resides in the provision of slidably interlocked guides or supports for mounting the drawers in the trunk section having means for receiving a locking device adapted to be engaged therewith to rigidly secure the drawers 35 against unauthorized opening.

With the above and other objects in view which will appear as the description proceeds, our invention resides in the novel construction, combination and arrangement of parts substantially as hereinafter described and more particularly defined by the appended claims, it being understood that such changes in the precise embodiment of the 40 herein disclosed invention may be made as come within the scope of the claims.

In the accompanying drawings, we have

illustrated one complete example of the physical embodiment of our invention constructed according to the best mode we have so far 55 devised for the practical application of the principles thereof, and in which:

Figure 1 is a vertical sectional view taken transversely through the drawer section of a wardrobe trunk on the plane of the line 1-1 of Figure 3, the central portion thereof being broken away and one of the drawers removed;

Figure 2 is a fragmentary perspective sectional view illustrating the device in a position locking one of the drawers, said view being taken through Figure 3 on the plane of the line 2-2;

Figure 3 is an enlarged fragmentary view, partly in section and partly in elevation, 70 taken through Figure 1 on the plane of the line 3-3;

Figure 4 is a fragmentary sectional view taken transversely through one side portion of the trunk drawer section on the plane of 75 the line 4-4 of Figure 3;

Figure 5 is a fragmentary perspective view of the master drawer illustrating the means carried thereby for actuating the device for locking the remaining drawers,

Figure 6 is a fragmentary, elevational view of the upper end of a drawer locking device detached from the trunk and constructed in a slightly modified manner;

Figure 7 is a view similar to Figure 3 of 85 a slightly modified means for actuating the locking bar;

Figure 8 is a fragmentary view, partly in section and partly in elevation, taken through Figure 7 on the plane of the line 8-8, and 90

Figure 9 is a fragmentary perspective view of the means for actuating the locking bar, the same being detached from the trunk and master drawer.

Referring now more particularly to the 95 accompanying drawings, in which like numerals designate like parts throughout the several views; the numeral 5 designates the drawer section of a wardrobe trunk having side, rear, top and bottom panels or walls 6, 100 7, 8 and 9, respectively, and adapted to be suitably connected with the wardrobe section or compartment, not shown, of the trunk. A plurality of drawers 10 are slidably mount-

ed in the drawer section for movement to closed position with their front faces substantially flush with the outer edges of the side panels. The upper-most drawer 10' of the plurality may be termed a master drawer, being equipped with an independent lock mechanism, not shown, having a locking bolt, not shown, which is adapted to be engaged in a keeper recess 11 in the top wall 8.

10 Each of the drawers is supported in the section 5 on a pair of drawer guide members or supports 12 secured to the side walls 6 in parallel relation and on the same plane. Each support 12 is preferably formed or bent from a blank or single strip of metal by being medially bent or folded along a longitudinal line, as at 13, to form a double thickness flange portion defining one side of a guide groove or channel 14, the other side of which is formed by further folding or bending the blank along a longitudinal line 15. The under side of the groove 14 is parallel with the upper side thereof and extends beyond the double flange to provide a supporting ledge or flange 16 on which the weight of the adjacent drawer 10 is supported.

15 The other longitudinal edge portion of the guide member 12 is directed upwardly at right angles to the double flange portion to provide an attaching flange which is suitably secured to the adjacent side wall of the section by rivets or other means 17.

20 Each drawer has a guide or support member 18 secured along each lower side corner thereof which is formed from a single blank or length of bendable metal folded or bent on a longitudinal line 19 with the top fold portion directed upwardly from a point spaced from but parallel to the fold line 19 to provide a vertical portion 20 adapted to be secured to the adjacent side wall of the drawer by rivets or other means 21. The under portion 22 of the double or two-ply ledge 23 thus formed extends inwardly beyond the portion 20 on a substantially straight line and is secured to the bottom of the drawer to, with the portion 20, reinforce the drawer. The extension ledge or guide flange 23 extended therebeyond is adapted to be slidably engaged in the groove or channel 14 of the adjacent section carried guide member 12.

25 The forward end portion of the flange or ledge 23 is preferably struck upwardly, as at 24, to provide a stop adapted to engage the inner end of the adjacent guide member 12 when the drawer is closed to limit its movement beyond a point with its outer face substantially flush with the outer edges of the walls of the drawer section. With this construction it will be readily obvious that the drawers are readily slidably mounted in the section 5 and may be moved to substantially full open position without requiring support 30 for their outer ends by reason of the inter-

locking engagement between the section and drawer carried guide members.

The drawers are adapted to be readily locked in closed position by locking tongues or keys 25 adapted to be inserted through openings or slots 26 and 27 in the sides of each channel 14 and in the adjacent ledges or flanges 23, respectively, which register when the drawers are in fully closed position. The locking tongues 25 are preferably formed of strip metal having their upper ends 28 parallel therewith but on a different plane and suitably secured by rivets 29 to a locking bar 30 vertically slidably mounted along the adjacent side wall 6 of the drawer section in alignment with the slots 26 of the section carried guide members 12.

35 As illustrated in the drawing, two locking bars 30 are preferably provided, one mounted at each side wall 6 and as but one need be employed if desired, the following description refers to the singular. The vertical attaching portions of the guide members 12 have guide strips 31 formed thereon in vertical alignment adjacent the slots 26 preferably by striking or bending the same inwardly, as best illustrated in Figures 2, 3 and 4, to a width and depth substantially equal to the width and thickness of the locking bar 30. The bar 30 is vertically slidably mounted in the bearings provided by the guides 31 and, as clearly illustrated, the locking tongues 25 are secured to the locking bar adjacent the members 12 with their free ends offset therefrom a distance substantially equal to the distance between the locking bar and the slots 26 so that vertical movement of the locking bar engages and disengages the locking tongues in the slots 26 and 27.

40 The upper end 32 of the locking bar 30 is preferably offset and has a stud or pivot pin 33 secured thereto which passes through an elongated opening 34 in the inner end of an actuating lever 35 having its outer end pivotally secured, as at 36, to the adjacent section 110 wall 6. The lever 35 is adapted to be in a substantially horizontal position when the locking bar is in downward position with the locking tongues engaged in the slots or openings in the guide members to rock the same 115 against relative movement. A contractile spring 37 having one end secured, as at 38, to the upper end of the locking bar and its other end secured, as at 39, to the section wall normally urges the locking bar upwardly to 120 a position with the locking tongues free of the guide grooves 14 of the guide members 12, as illustrated in dotted lines in Figure 3.

45 The locking bar is depressed against the action of the spring 37 by an actuating member 40 secured to the adjacent side wall of the master drawer 10' and adapted to ride over the upper surface of the lever 35 as shown in Figure 1 as the drawer is moved to closed position to have a cam action thereon and 125 130 135

press the same downwardly against the spring 37, as will be readily apparent. An opening of the drawer 10', disengaging member 40 from the lever 35, permits the upward return of the locking bar under the action of the spring 37 and unlocks the remaining drawers 10.

In Figure 6 is illustrated a slightly modified form of our invention in which the lever 35 is of bell-crank form having its pivotal connection 36 at the apex thereof and its short arm 41 normally extended upwardly in the path of the drawer carried actuating member 40 to be moved inwardly by closing movement 15 of the drawer 10' to depress the outer end of the other arm thereof and consequently the locking bar 30.

In operation it will be readily obvious that the drawers 10 are moved inwardly to fully closed position and, closing movement of the master drawer 10' engages the actuating members 40 on the opposite sides thereof with the adjacent levers 35 depressing the locking bars 30 to engage the tongues 25 in the registered apertures 26 and 27 of the adjacent guide members 12 and 18. The master drawer 10, is then locked closed by its independent or master lock, not shown, and the drawers 10' are consequently locked until the master drawer is opened sufficiently to disengage the members 40 and the levers 35.

In Figures 7 to 9, inclusive, another type of means is illustrated for actuating the locking bar 30, this means being so designed and constructed as to insure the positive unlocking movement of the bar 30, a spring being provided for primarily retaining the bar inoperative and assisting the opening movement thereof. In this form of our invention, the lever 35 is medially provided with an elongated slot or opening 42 in which is positioned a pin or stud 43 medially carried by a link or lever 44 having one end pivotally secured, as at 45, to a plate 46 to which the lever 35 is pivoted. A pin or projection 47 is formed on the other free end of the lever 44 and normally lies in the path of the actuating member 40 carried by the adjacent side of the master drawer 10'.

In this form of our invention, the spring 37 has one end secured to the adjacent trunk panel, as at 39, and its other end secured to the lever 35 adjacent its pivot 33. With this construction it will be readily evident that the locking bar 30 is normally yieldably retained in inactive position and movement of the free end of the lever 44 to its dotted line position illustrated in Figure 7, by engagement of the member 40 with the pin 47 thereof depresses the outer end of the lever 44, carrying with it the bar 30 to engage the locking tongues 25 thereof in the registered apertures of the interlocked slide members. When in locking position, the center of pivot 43 is preferably slightly beyond an imaginary line drawn ver-

tically through the pivot 45 to thus secure the bar in locked position against the action of the spring.

The actuating member 40 illustrated in Figures 7, 8 and 9, has its outer end portion 50 offset and parallel to the adjacent side of the drawer and is provided with a vertical recess 51 the outer end 52 of which is cut away sufficient to pass under pin 47 when the bar is in its upper-most position. As a result, closing movement of the drawer 10' engages the extended wall 53 of the recess 51 with the pin 47, moving the bar to locking position and engaging the pin in the recess. Opening movement of the drawer 10' insures the positive return of the locking bar, the pin 47 being carried to its dotted line position by the end 52 of the actuating member.

In Figures 7 and 8, the locking bar 30 is illustrated as secured to one side panel of the trunk, although it will be readily evident that two may be employed if desired, although one is sufficient.

The forward or outer end of the ledge 16 of each panel carried guide member is preferably provided with a guide extension or tongue 54 to provide means for facilitating the insertion of the drawers in the trunk. The inner end of the drawers are positioned thereon and consequently the flanges 19 thereof are guided into the channels 14.

From the foregoing description taken in connection with the accompanying drawings, it will be readily apparent to those skilled in the art to which an invention of this character appertains that we provide an improved drawer guide and drawer locking device which is concealed within the drawer section, which is easily actuated by the closing movement of the master drawer and which affords maximum protection against tampering with or the unauthorized opening of the trunk drawers.

What we claim as our invention is:

1. In a device of the character described including a drawer receiving section having side walls and a drawer slidable therein, drawer guide members secured to the section side walls, guide members carried by the drawer and slidably interlocked with the first-named guide members, a bar member slidably mounted at one section side wall, and means carried by the bar and adapted to be passed through registering apertures in the guide members to lock the interlocked guide members against relative movement when the drawer is closed.

2. In a device of the character described including a drawer receiving section having side walls and a drawer slidable therein, drawer guide members secured to the section side walls, guide members carried by the drawer, the adjacent guide members being longitudinally slidably interlocked to prevent vertical movement of the members, a ver-

tical bearing carried by one section guide member, a bar vertically slidably mounted in said bearing, and a locking tongue carried by said bar and adapted to be engaged in registered apertures in the adjacent guide members when the drawer is fully closed to secure the drawer in such position.

3. In a device of the character described including a drawer receiving section having 10 side walls and a drawer slidable therein, drawer guide members secured to the section side walls, guide members carried by the drawer and slidably interlocked with the first-named guide members, a vertical bearing carried by one section guide member, a bar vertically slidably mounted in said bearing, a locking tongue carried by said bar and adapted to be engaged in registered apertures in the adjacent guide members when 15 the drawer is fully closed to secure the drawer in such position, and means normally yieldably urging said bar to a position disengaging the locking tongue from the members to permit free movement between the 20 guide members.

4. In a device of the character described including drawers receiving section and a drawer slidable therein, a locking bar mounted in the section, cooperating means carried 25 by the locking bar and one drawer whereby depression of the locking bar secures said drawer in closed position, a lever means pivotally connecting one end of the lever with the section, means pivotally connecting the 30 other end of the lever with the upper end of the locking bar, a second lever, means pivot-

ally connecting one end of the second lever with the section, a pivot pin medially carried by the second lever and engaging in an elongated slot medially formed in the first lever, 40 a projection carried on the free end of said second lever, and an actuating member carried by the other drawer and adapted to engage said projection upon closing movement to move the second lever on its pivot and depress the outer end of the first lever and consequently depress the locking bar. 45

5. In a device of the character described, including a drawer receiving section, a pair of horizontally disposed drawer guide members fixed to the opposite side walls of the section and provided with spaced horizontal flanges forming a channel therebetween, guide members carried by the drawers and having a part projected laterally to be slidably received between the spaced flanges of the fixed guide members whereby the drawer is mounted for sliding movement in and out of said section but is prevented from vertical movement, a bar vertically slidably mounted in the section along one side wall, a locking tongue carried by said bar and having its end portion offset therefrom, but parallel thereto and adapted to be passed through apertures in the flanges of the adjacent guide members, and means for moving said bar to engage and disengage said locking tongue in the guide member apertures. 55

In testimony whereof we affix our signatures.

GEORGE HENRY WHEARY.
MATHIES KURTEN.

CERTIFICATE OF CORRECTION.

Patent No. 1,686,194.

Granted October 2, 1928, to

GEORGE HENRY WHEARY ET AL.

It is hereby certified that error appears in the printed specification of the above numbered patent requiring correction as follows: Page 4, line 27, claim 4, after the word "including" insert the article "a", and for the word "drawers" read "drawer", and after the word "and" strike out the article "a"; same page and claim, line 28, for the word "drawer" read "drawers", and line 32, after the word "lever" insert a comma; and that the said Letters Patent should be read with these corrections therein that the same may conform to the record of the case in the Patent Office.

Signed and sealed this 27th day of November, A. D. 1928.

(Seal)

**M. J. Moore,
Acting Commissioner of Patents.**
